UNITED STATES PATENT OFFICE

HENRY A. BUCK, OF PROVIDENCE, RHODE ISLAND, ASSIGNOR TO CHARLES D. WAINWRIGHT,
OF MARBLEHEAD, MASSACHUSETTS.

CYLINDER-HEAD.

No. 880,478.

Specification of Letters Patent.

Patented Feb. 25, 1908.

Application filed January 30, 1907. Serial No. 354,863.

To all whom it may concern:

Be it known that I, HENRY A. BUCK, a citizen of the United States, residing at the city of Providence, in the county of Providence and State of Rhode Island, have invented 5 certain new and useful Improvements in Sheet-Metal Cylinder-Heads, of which the following is a specification, reference being had therein to the accompanying drawing.

10 This invention relates to improvements in the construction of cylinder heads, covers and the like, and has for its object to provide a cylinder head or cover that is constructed of sheet or plate metal the same being particularly adapted for use on pump and engine 15 cylinders but serving equally well as a cover or head for receptacles of any kind in which heavy pressures of liquids or gases may be required to be confined.

20 The particular feature of this invention is that these heads are constructed entirely of sheet or plate metal either steel or of any other suitable material capable of being stamped, pressed or swaged by suitable dies 25 or punches into the desired shape.

Another feature of the invention is that this head is constructed of a plurality of plates arranged and formed to reinforce and support each other in such a manner as to 30 give great strength to the construction.

35 My improved cylinder head has many advantages over the old form of cast-iron heads, among others being, first, the increased strength of construction which is, to say the least, over three times that of any form of casting; second, great saving in weight; third, great increase in the elasticity, the possibility of breakage being reduced to a minimum; fourth, economy in cost of construction, as 40 has been proved in practice, a cylinder head formed with punches and dies can be produced complete for much less than would be the cost of the cheapest casting of the same diameter, without considering the expense of 45 finishing the same; fifth, economy of time in manufacture. The various stampings or parts can be manufactured, assembled and finished in less time than it requires a workman to set the work and take one chip across 50 the face of an ordinary cast head of equal diameter. Then again, when the parts are constructed by die work they are all perfectly

true and may be exactly duplicated, all the parts being thus rendered interchangeable. The quality of the material and the manner 55 in which the head is constructed renders the same practically indestructible.

A practical embodiment of the invention is represented in the accompanying drawings, forming a part of this specification in which 60 similar characters of reference indicate corresponding parts in all the views.

In the accompanying drawings: Figure 1—is a sectional view showing a form of cylinder head adapted to allow the piston rod or driving shaft to pass therethrough, the same being constructed entirely of sheet material. Fig. 2—is a detail showing the outer head plate in section. Fig. 3—is a detail showing the inner head plate in section. Fig. 4—is a 70 detail showing the binding nut in section. Fig. 5—is a detail showing the binding collar in section which is adapted to be screwed into said binding nut for the purpose of firmly securing the center portion of the head together and forms a bearing therein. Fig. 6—is a detail in section of the packing gland. Fig. 7—shows a portion of a cylinder and a modified form of head where the inner plate is plain, an intermediate bracing plate being 80 located between the inner and outer plates, and showing the center portion of said outer plate turned inward onto the intermediate plate to support, strengthen and stiffen the whole. Fig. 8—shows a detail in section 85 of an intermediate reinforcing or bracing plate.

Referring to the drawings the inner head plate 1 is preferably cut in the form of a circular disk from sheet material an annular 90 flange 2 being formed thereon by pressing upward or raising the circular flange portion thereby forming the lip 3 which is adapted to fit closely into the end of the cylinder 24, as shown in Fig. 7. To form the construction 95 illustrated in Fig. 1 the center portion of this plate is pressed outward from the inner face of said plate providing a central circular aperture 4 around which is formed the annular flange collar 5, which collar serves as a center 100 support and greatly increases the strength of the plate. The outer head plate 6 is also provided with a flange portion 7 raised from its outer face, the stock being preferably car-

ried around in a circular form, as shown at 8, to increase the strength and at the same time lend grace and beauty to the design. The face of this flange 7 corresponds in size 5 and is adapted to register with the flange 2 of the inner plate 1. The center portion of this outer plate is like plate 1 swaged inward providing an aperture 9 around which is formed the annular flange collar 10. The inner diameter 10 of this collar 10 is made a trifle less than the outer diameter of the flange collar 5 so that when these outer and inner head plates are brought together their center portions must be forced one within the other 15 thereby providing a true central bore surrounded by a metal wall of double thickness. Through the flanges of these plates may be punched as many bolt holes 25 as desired. At 11 is a tubular binding collar, also constructed 20 of sheet material, and having a shoulder or head 12 turned or pressed outward at one end and being threaded at 13 for a portion of its length on its outer surface from its opposite end. At 14 is a binding 25 nut also pressed up from sheet material having a shoulder or flange 15 at its outer end and having its opposite end flared or turned outward at 16 so as to receive a more perfect bearing where it comes in contact with the 30 upper surface of the outer plate, the inner surface of this nut being threaded at 17. At 18—18 are tapped holes in said flange into which the packing gland studs 19—19 are screwed.

35 In order to secure the outer head plate and the inner head plates permanently together the binding collar 11 is adapted to fit tightly in and is forced through the center bore 4 of the head from the inside outward and onto 40 its outer end is screwed the binding nut 14 thus securely locking the two heads tightly together rendering the joint absolutely steam tight. The packing gland 20 may also be made of sheet metal and is provided with a 45 flange 21 through which the holes 22 are formed for the reception of the gland studs 19, the body portion of this gland being adapted to fit closely into the bore of the binding collar, as shown in Fig. 1. Into this 50 gland may be forced a removable and renewable bearing bushing 23 which may be formed of any suitable journal metal. A bushing 24 of a similar character may also be forced into the opposite end of the binding 55 collar 12 the whole forming a bearing for a shaft of a simple and practical construction packed with a suitable stuffing box:

60 A feature of my improved construction is that the head being constructed of a plurality of plates may be formed hollow providing a chamber between the plates, as illustrated in Figs. 1 and 7. This chamber may serve either as a cooling or heating jacket by receiving a circulation of either

water or steam. In order to provide an inlet and outlet to this hollow head the outer plate 6 may be swaged outward as at 26 and a nipple 27, threaded at its outer end, is forced into the aperture and expanded therein to form a steam tight fit, and if it is desired to pass the contents of the head into the cylinder suitable apertures, not shown, may be made in both the inner head plate 1 and the intermediate brace plate 28. In order to stiffen the head any number of brace plates 75 may be formed to fit into the interior of the head between the inner and outer plates and arranged in any convenient manner, and where the surface of the inner plate 1 is plain, as shown in Fig. 7, the plates may all be securely locked together by means of the cylinder head bolts 29 placed at close intervals 80 around the flange.

85 My invention is not restricted to the construction and arrangement of parts herein shown and described nor to the various details thereof as a head constructed in any form of a plurality of plates of sheet material arranged to reinforce and support each other would come within the spirit and scope of 90 my invention, one practical embodiment of which has been herein illustrated and described without attempting to show all the various forms and modifications in which my invention might be embodied.

95 Having thus described my invention, what I claim as new and desire to secure by Letters Patent, is:

1. A cylinder head constructed of a plurality of sheet metal plates, said plates being 100 so formed as to engage and support each other.
2. A cylinder head constructed of a plurality of sheet metal plates, said plates being bent to engage and support each other at a 105 plurality of points.
3. A cover or head constructed of a plurality of sheet metal plates, said plates being bent to engage and support each other, and means for securing said plates together. 110
4. A cover or head constructed of a plurality of plates, said plates being bent and secured together so as to form a chamber between them, said plates being also bent so as to reinforce and support each other. 115
5. A cylinder head constructed of a plurality of sheet metal plates, said plates being bent to engage and support each other at a plurality of points so that when in their operative position they form a hollow head, 120 and means for securing said plates together.
6. A cover or head constructed of a plurality of plates including an inner plate, an outer plate and an intermediate supporting brace plate, and means for securing said 125 plates together.
7. A cylinder head constructed of a plurality of plates, said plates being bent to en-

gage and support each other, and means whereby said plates are secured together through their center portion.

8. A cover or head constructed of a plurality of plates including an inner plate, an outer plate and an intermediate supporting brace plate, and means passing through the center portion of said plate for securing them together.

10 9. A cover or head constructed of a plurality of plates, said plates being bent and secured together so as to form a chamber between them, said plates being also bent so as to reinforce and support each other, and 15 means for securing said plates together through their central portion.

10. A cover or head constructed of a plurality of stamped sheet metal plates, including an inner plate and an outer plate, said 20 plates being arranged to support each other at a plurality of points and to provide a chamber between them, and means in said head whereby a circulating medium may be admitted thereto.

25 11. A cover or head constructed of a plurality of sheet metal plates including an inner plate and an outer plate, said plates being bent to support each other at a plurality of points and to provide a chamber between 30 them, means in said outer plate whereby a circulating medium may be admitted to said chamber, and means for securing said plates together.

35 12. A cylinder head constructed of a plurality of sheet metal plates including an inner plate and an outer plate, said inner plate being swaged to form a flange, and a lip extending below said flange to engage the inner wall of the cylinder to which said head may 40 be secured, and means for securing said plates together.

45 13. A cover or head constructed of a plurality of sheet metal plates an inner plate and an outer plate, said plates being arranged 50 to support each other and to provide a chamber between them, said inner plate being swaged to form a flange, and a lip extending below said flange to engage the inner wall of the cylinder to which said head may be secured, and means for securing said plates together.

55 14. A cover or head constructed of a plurality of sheet metal plates including an inner plate and an outer plate, said plates being bent to support each other at a plurality of points and to provide a chamber between them, means in said outer plate whereby a circulating medium may be admitted to said chamber, and means whereby said plate may 60 be secured together through their central portion.

15. A cover or head constructed of a plurality of sheet metal plates including an in-

ner and outer plate, said plates being arranged to support each other and to provide 65 a chamber between them, the center portion of one plate being turned back to meet the opposite plate thereby providing a central bore through the head, and means extending through said bore by which said 70 plates are secured together.

16. A cover or head constructed of a plurality of sheet metal plates including an inner plate and outer plate, said plates being arranged to support each other and to provide 75 a chamber between them, the center portion of each plate being formed into an annular flange collar adapted to be forced one within the other when the plates are brought together to provide a central bore 80 through the head.

17. A cover or head constructed of a plurality of sheet metal plates including an inner plate and outer plate, said plates being arranged to support each other and to provide 85 a chamber between them, the center portion of each plate being formed into an annular flange collar adapted to be forced one within the other when the plates are brought together to provide a central bore 90 through the head, and means extending through said bore for securing the plates together.

18. A cover or head constructed of a plurality of sheet metal plates including an inner plate and outer plate, said plates being arranged to support each other and to provide a chamber between them, the center portion of each plate being formed into an annular flange collar adapted to be forced 100 one within the other when the plates are brought together to provide a central bore through the head, a tubular binding collar adapted to pass through said bore, said collar having a shoulder at one end and a 105 tubular binding nut threaded to its opposite end whereby the plates of said head are rigidly secured together.

19. A cover or head constructed of a plurality of sheet metal plates including an inner plate and outer plate, said plates being arranged to support each other and to provide a chamber between them, the center portion of each plate being formed into an annular flange collar adapted to be forced 115 one within the other when the plates are brought together to provide a central bore through the head, and a shaft bearing and stuffing box provided within said central bore.

120 20. A cover or head constructed of a plurality of sheet metal plates including an inner plate and outer plate, said plates being arranged to support each other and to provide a chamber between them, the center 125 portion of each plate being formed into an

annular flange collar adapted to be forced one within the other when the plates are brought together to provide a central bore through the head, a tubular binding collar 5 adapted to pass through said bore and a tubular binding nut threaded to the opposite end of said collar whereby the plates of said head are rigidly secured together, and a shaft

bearing and stuffing box provided within said tubular binding collar.

In testimony whereof I affix my signature in presence of two witnesses.

HENRY A. BUCK.
